UNITED STATES PATENT OFFICE.

BENJAMIN FRANKLIN HUTCHISON, OF LOS ANGELES, CALIFORNIA.

ART OF PHOTOGRAVURE COLOR PRINTING.

Application filed January 3, 1922. Serial No. 526,523.

This invention relates to prints produced by different colored inks on a common surface, and includes the finished print, the plate and other devices produced by, and employed in, the operation of producing such print, and the method by which such print, devices, and plate, are produced.

The carrying out of this invention involves a new process for producing supplementary printing plates, which, when printed in connection with photographic half-tone printing plates in suitable colors of ink, will produce color prints similar in appearance to prints known to photo engravers as duotones; or, if two supplementary plates be used with proper inks, the result is a print similar in appearance to those known to photo engravers as tricolor prints; and with three supplementary plates, used with the proper inks, a print similar to those known to photo engravers as quadricolor is produced. The results are not identical, but they are similar.

The supplementary plates produced by my improvement in this art may also be printed as supplementary color plates to line-etched plates; either one or more supplementary plates being used with suitable colors of ink, producing a result differing from anything now used by photo engravers, but somewhat similar in appearance to the result attained by what is known to photo engravers as the Ben Day process, although this newly discovered method of production is entirely different from, and more economic of operation, than any process heretofore known.

Objects and advantages of this improvement are:

To produce color printing plates and multicolor prints at less expense than heretofore.

To produce photographic half tone supplementary color plates to print in connection with photographic half-tone plates made at a previous time.

An object of this invention is to enable the owner of an ordinary photographic half-tone plate, which he has already purchased and probably used in the production of one-color printing, to utilize such plate for the production of multicolor prints.

Another feature of the invention is the predetermining of the characters, the amounts, and the locations of colors that are required to produce the desired effect in

the combined impressions of the several plates.

Other objects, advantages and features of invention may appear from the accompanying drawings, the subjoined detailed description and the appended claims.

An object of this invention is to so prepare camera copy for photographic half-tone supplementary color plates, that in making the negative therefrom a prism attachment may be used upon the camera, and the camera copy may be photographed through the celluloid upon which it has been prepared, thereby gaining the advantages of photographing the camera copy through a prism, and of photographing it through celluloid and also of avoiding the necessity of the photo engraver stripping the negative from the glass plate, upon which it was photographed, and transferring it in reversed position to another glass plate prior to printing the image upon the printing plate to be etched. Where the lines of two or more plates must register, one upon another, it is necessary to avoid transferring the negative, which has a tendency to lose its shape during the transfer.

An object of this invention is to avoid the danger or likelihood of any distortion of the negative either from camera vibration or negative displacement during the operations of preparing the negative for printing upon metal.

It is desirable in producing negatives from camera copy for the production of photographic half-tone supplementary color plates, that a camera of fixed focus be used to insure correct register of the supplementary plate with the key plate; and it is also desirable to print the negative through the use of a prism attachment so that the camera copy can be more rigidly placed in a square position with relation to the photographic plate, thereby preventing distortion of the negative.

In the production of a photographic half-tone supplementary color printing plate, I produce through a prism, a camera copy negative in correct position on its plate, for immediately printing upon the metal, without stripping, removing, reversing or displacing the negative from its plate.

In carrying out this invention, the camera copy for the production of the photographic half-tone supplementary color printing plate is prepared upon a sheet of

thin mat celluloid in such a manner that by reversing the sheet and photographing the camera copy through the celluloid, while using a prism attachment to the camera, a negative is produced in the correct position to be printed upon the metal, thus avoiding any likelihood of distortion or relative displacement of parts of such negative.

An object is to secure a greater smoothness of surface in the camera copy; that is to say, an absence of any appearance of brush marks in the finished plate.

Another object is to facilitate properly placing high lights, shadings and details in the correct position for registry with the key plate when such high lights shading or details, appear in connection with colors in the supplementary plate.

In this broadly new and pioneer method, I provide and use one or more tone determiner proof sheets and preferably a sheet which is a photo-engraved multiple shade sheet and may have the various shades arranged in regular or irregular forms, as spots, blotches or stripes. A regular arrangement of regular stripes is preferred, and will be illustrated herein.

The accompanying drawings will assist in the understanding of the new discovery and invention.

Figure 1 represents a specimen of the preferred type of tone determiner; a sheet of multiple-shade proof-paper printed from a photo-engraved printing plate and adapted for use in one of the steps involved in my improvement in this art. Orange is the color shown in this instance.

Fig. 2 represents fragments of similar tone determiner or proof sheets, of different colors; viz, blue, purple, and yellow.

Fig. 3 represents a key or tint-guide sheet for use in this improved art; the same, in this illustration, comprising two sets of stripes; the stripes of one set being in angular relation to the stripes of the other set; the stripes of each set varying in intensity, as from black to very light grey in one set, and from solid orange to a light orange tint in the other, showing numerous combinations of two colors.

Fig. 4 is a view of a like key or tint-guide sheet, showing another combination of two colors in numerous tints.

Fig. 5 is a fragmental view of a key or tint-guide sheet of another combination of two colors.

Fig. 6 is a fragmental view of a celluloid mat tone determiner camera-copy for use in, or toward, the production of what is shown in Figs. 1, 2, 3, 4, 5, 7, 8 and 10.

Fig. 7 is a fragmental view of a multiple-shade print from a half-tone proof-paper printing plate made from the celluloid mat shown in Fig. 6.

Fig. 8 is a fragmental view of a multiple-

shade print from the same proof-paper printing plate, as Fig. 7, printed with another color.

Fig. 9 is a guide print made by offsetting on a thin sheet of celluloid, an ink impression from the key plate and is to be used in making camera-copy for the half-tone supplementary printing plate.

Fig. 9^a is a fragment of a photo-engraved key plate.

Fig. 9^b is an ink proof from the key plate.

Fig. 10 is a view of the tone determiner proof, being in this instance a striped multiple-shade sheet of red proof-paper with the impression thereon of the photo-engraved printing plate from an impression of which Fig. 9 is an offset.

Fig. 11 is a view of the workman's shade kit containing one white, one solid black, and several shades of grey, oil or water color, and the color characters appropriate thereto.

Fig. 12 is a fragmental view of a celluloid camera-copy made from the guide print shown in Fig. 9.

Fig. 13 is a print from a half-tone printing plate produced by painting the reverse side of the celluloid guide print sheet shown in Fig. 9, and then erasing the guide print from said sheet, in the usual manner; the negative for its production being made by the reverse side of the celluloid camera copy shown in Fig. 12.

Fig. 14 is a view of the finished product which is a print comprising an impression in one color, of a photographic half-tone printing plate, or a line-etched printing plate, forming a picture; and an impression in another color, of a photographic half-tone printing plate of portions of said picture in varying shades; and may be with or without additions to said picture.

Fig. 15 is a view of a set of five sheets of red tone determiner proof paper by the use of which it is possible to predetermine the shades or tints for a supplementary plate adapted for printing the supplementary impression shown in Fig. 14.

The method used in producing supplementary color printing plates by this process is as follows:

First: The working colors are prepared. They may be of any photographically suitable character and are preferably black and several shades of grey. The colors and shades or tints are designated throughout the paraphernalia or devices employed by the workman, by corresponding color characters *a*, for the applied paints and *a'* for the unapplied paints, and which are shown as Arabic numerals; the numeral "1" being used for the solid color and successive numerals as "2", "3", "4", and "5" being used for the successively lighter shades or tints thereof. It is necessary that uniformity of thus arranging the colors, shades or tints

be followed in the case of learners or ordinary workmen and it is essential to this process that the exact formula of color and shades or tints thereof adopted for the use of 5 the workmen shall be maintained throughout the process.

Preliminary to beginning the production of the supplementary printing plate, the workman will be supplied with the requisite 10 working colors or paints *b* which, for convenience and to avoid mistakes are designated on the color tray *t* with the numerals indicated by the color characters *a*.

A stock of proof paper sheets for the purpose of predetermining the proper tints or 15 intensities of color desirable in the various parts of the supplementary color printing plate or tint plate to be produced, is printed with inks of the various colors usually used 20 as the supplementary colors for the finished prints, and is kept on hand, ready for use as required. Each sheet of such proof paper is printed in one color which usually comprises sections of different shades or tints 25 and is called the tone determiner. Specimens of various tone determiner proof sheets are shown fresh in Figs. 1 and 2, and such sheets are marked with the character *c* wherever any specimen is shown in 30 the drawings. See Figs. 1, 2 and 10.

This multi-tint tone determiner *c* is prepared as follows: A sheet *d* of thin mat celluloid having a smooth side is painted on the mat side with the entire succession of 35 working colors or paints *b* (see Fig. 11) decided on for use throughout the process. These paints are preferably photographically suitable water colors and they are applied in sections, most desirably in bands or 40 stripes *b'*, of black and greys in successively lighter shades. See Fig. 6.

The sections of like color or tints are respectively marked throughout with the appropriate designating character "1", "2", 45 "3", "4", or "5" as indicated by *a'* in said Figs. 1, 2 and 10 and other views.

This sheet of celluloid *d* is reversed and a photographic negative of the reversed sheet photographed through the celluloid, 50 is produced, and its image is flat etched upon copper or zinc in the manner usual to photographic half-tone processes, thus producing a photoengraving showing varying intensities of shade, the ink impressions from 55 which constitute the multiple-shade print *c'*, Figs. 7 and 8, and will of course, exhibit the same relative intensity of shades irrespective of the color in which the impression is printed. With such copper or zinc cut, 60 not shown, I print the tone-determiner paper sheets *c*.

In producing the tone determiner proof paper sheets *c*, black and shades of grey have been indicated for camera copy; but 65 any color and shades and tints thereof may

be used. It is essential to this process, that the exact formula of black and shades of grey, or color and tints or shades thereof, that is selected for any production shall be used throughout the production of the tone 70 determiner, *c*, and all the other devices used in this improved art, for the purpose of determining intensity of color in the supplementary plates. The tone determiner sheet 75 should be preserved as record, and the same formula always be used by the workman in preparing camera copy for supplementary plates, as hereinafter described.

Second: Tint guide sheets, *e*, as in Figs. 3, 4, 5, are prepared for the purpose of observing the color phenomena which results from the printing of different colored inks on a common surface as governed and modified by the density of half-tone dots. This tint guide sheet is used by the workman as an 80 auxiliary to the tone determiner proof sheet *c*, in preparing camera copy for supplementary plates. It is also used by the artist in preparing the copy for key plates *p*, and by any person directing the work of such 85 artist and workman to determine the possibilities of color and shades of any two inks printed upon a common surface.

This tint guide sheet, *e*, is prepared as follows: A photoengraved cut is made as 90 described for the production of tone determiner sheets in bands of color and shades thereof or other convenient arrangement, the angle of the dot in imposing the photographic half-tone screen, being 45 degrees. 100 A second photoengraved cut of the same copy is then made, the angle of the dot being 30 degrees. An ink impression from the first cut is printed with the striped sections or bands 1, 2, 3, and 4 running horizontally with the paper. An ink impression from the second cut is printed upon the common surface, with the lines running perpendicularly; the first engraving represents 105 the tint in solids, middle tones and highlights, and the second engraving represents the key in solids, middle tones and highlights. These tint guide paper sheets, or 110 key sheets, are prepared in the two colors of ink which it is desired to use in combination and in as many varieties of combinations of such two colors and their tints and shades as is required.

Third: A proof *f* of the photo-engraving or line-etched plate for which it is desired to produce a supplementary tint plate or plates and which is hereinafter referred to as the key plate, shown at *p* in Fig. 9^a, is made upon a sheet *c* of the tone determiner paper previously prepared in the exact color in 115 which it is intended the supplementary tint plate is to be produced. The impression *f* of the key plate is printed upon the tone determiner proof sheet *c*, Fig. 10, in the exact color in which it is intended to be print- 120 125 130

ed in the finished two-color print, *g*, shown in Fig. 14, for the reason that colors printed in combination produce a variety of secondary colors and shades as in Figs. 3, 4, 5, 10, and 14.

A tint guide sheet *e*, see Figs. 3, 4, 5, is printed in the exact inks which are intended to be used in the key plate print *f* and tint plate, print *o*, Fig. 13, and is also referred to by the workman, as an auxiliary to the tone determiner sheet *c*.

Fourth. A print, *g* shown in Fig. 9^b, is then made in strong red ink from the key plate, and an offset impression *h* thereof (see Fig. 9) is made on the smooth side *n* of a sheet *d'* of thin mat celluloid. This celluloid sheet *d'* is then reversed as shown in Fig. 9 and the workman supplied with the black and grey paints *b* exactly alike in formula to the paint used in producing the camera copy from which the engraver produced the photoengraving, plate *p*, used in making the tone determiner proof paper *c* shown in Figs. 1, 2 and 10 and making the guide sheet *e*, Figs. 3, 4 and 5, and tone determiner paper *k*, Fig. 15.

The sheet *d'* of celluloid shown in Fig. 12 is used by the photoengraver as camera copy from which to make the negative used in producing the supplementary plate photoengraving.

The key plate impression *g* is preferably printed in red in order to enable the workman to most readily distinguish the details of the guide print *h* on the smooth underside *n* of the celluloid sheet *d'*, through the celluloid while painting the camera copy on the mat side of the celluloid with black and shades of grey. If any other color than strong red be used for the guide print, the lines thereof will not be so easily distinguished while painting with black and grey on the mat side *m*.

It is essential to this process that the workman shall always use colors of the same formula (and therefore the same shades) as were used in making the photoengravings from which the tone determiner proof papers *c*, *k* and tint guide sheets *e* were produced.

The workman then proceeds to paint camera copy *i*, (Fig. 12), on the reverse side of the celluloid sheet *d'* through which he can see the red offset print *h*, of the key plate, which serves as the workman's guide as to where to paint. While doing this the workman has before him the tint guide sheet *e*, Fig. 4 and the tone determiner proof, as in Fig. 10, which furnish him with a mechanically accurate guide as to the shade of grey or black with which to paint, to secure the proper intensity of shade in the supplementary plate, and to produce the desired color and tint in the finished color print. The tone determiner proof *f*, Fig. 10, of the

key plate shown in Fig. 9^a is printed in the color to be used in printing from the key plate in the finished color print shown in Fig. 14, and is printed upon tone determiner paper of the color and shades thereof to be used in printing the supplementary plate in the finished print.

The success of this process depends on the workman painting the proper shades of black and grey on the camera copy *i*, Fig. 12; and to enable him to do this I provide a guide proof combining the color and the densities thereof in the key plate impression *f* with the color and the densities thereof which it is proposed to use in printing in the finished print, the supplementary color, shown, for instance pink or red, as indicated at *j* in Figs. 4, 10, 14 and 15.

An advantage of using multiple tint tone determiner proof paper *c* is that it makes it easy for the workman to compare various tones, i. e., solids, middle tones and highlights.

For great exactness, the workman will be provided with one proof of the key plate printed on tone determiner proof paper *c* having the bands of color as in Fig. 10; and will also be provided with other proofs of the key plate, each printed on a full sheet, thus forming a set of tone determiner proof paper sheets each composed of one single tint or shade, as in Fig. 15. In painting camera copy for the tone determiner tint guide sheet and for painting camera copy for supplementary plates, I use a sufficient number of such solids, tints and shades as are most practical for ordinary commercial purposes, i. e., four, more or less as may be desired.

Fifth. The offset print *h* of the key plate used has a guide print by the workman in painting, the camera copy is now erased from the celluloid *d'* by sponging with benzine; and then a photographic half-tone negative, not shown, is made of exactly the same size as the camera copy *i*. It is advisable to use for this purpose a fixed focus camera equipped with a prism.

The camera operator will ascertain the angle of the dots of the screen in the key plate and place the camera copy *i* upon the camera copy board (not shown) in such position that the angle of the half-tone dot in the negative of the supplementary plate will vary thirty degrees from the angle of the half-tone dot in the key plate, in order that the half-tone dots in the key plate and supplementary plate may properly register.

In making this negative the camera copy is photographed with the mat side *m* of the celluloid on which the camera copy *i* is painted, away from the lens, thus photographing through the celluloid; the smooth side *n* of the celluloid sheet *d'* from which the guide print *h* has been erased, being

toward the camera. Since the guide print *h* was an offset upon the celluloid, the camera copy *i* when viewed from the side of the celluloid upon which it was painted is 5 also in reverse; but when the celluloid is reversed in its exposure to the camera the position of the camera copy is corrected for photographing through the prism attachment which will thus impose the negative 10 in the proper position to be printed upon the metal plate.

After the negative made from the camera copy *i* is printed upon the copper or zinc plate, it is etched in the usual manner, producing the supplementary printing plate 15 with which the supplementary print *o*, Fig. 13, may be printed. By printing with the key plate and the supplementary plate in the usual way and with the selected inks, 20 the final two-color print *g*, Fig. 14, is produced.

I claim.

1. The method set forth of producing a half-tone printing plate which comprises 25 painting the camera copy for a supplementary print, with colors corresponding in actinic value to the shades of color required in the finished print, and thus predetermining the tones to be produced from said half-tone printing plate.

2. The method set forth of preparing camera copy for a supplementary plate to be used in conjunction with a key plate for producing superposed impressions to form a 35 print, which method consists in printing an impression of the key plate making an offset of said impression upon a thin, transparent celluloid sheet, painting the camera copy upon the other side of said transparent 40 sheet of celluloid, using said key plate impression as a guide viewed through the celluloid, for determining the places where the paint is to be applied, and whereby the camera copy is adapted to be photographed 45 through a prism in producing the negative for the supplemental print.

3. The method set forth of preparing camera copy for a supplementary plate to be used in conjunction with a key plate for 50 producing superposed impressions to form a print, which method consists in painting the camera copy upon the mat side of a

transparent sheet of mat celluloid, having a smooth side upon which is an impression of the key plate so that the key plate impression may serve as a guide viewed through the celluloid, for determining the places where the paint is to be applied, and the camera copy is adapted to be photographed through a prism in producing the negative 60 for the supplemental print.

4. The method set forth of preparing camera copy by a supplementary plate to be used in conjunction with a key plate for producing superposed impressions to form 65 a print, which consists in painting the camera copy upon one side of a transparent sheet of celluloid upon the other side of which is an impression of a key plate so that the key plate impression may serve as a guide 70 through the celluloid for determining the places where the paint is to be applied; and predetermining the tones and shades by using paints of various shades indicated by a guide print made up of dots uniform to 75 each shade.

5. In the art of producing poltyone prints, the method of predetermining the tones of a supplementary printing plate which consists in painting the camera copy therefor 80 with paints of various shades and predetermining the shades or tints or tones of the finished print by a tone determining guide sheet having a key plate impression thereon, and a tint guide sheet containing sections of tints, tones or shades corresponding to tints, tones or shades required in the desired print.

6. The art of producing poltyone prints set forth which consists in using paints of 90 one color in various shades and densities to paint camera copy for a supplementary plate in various shades representing tone determiner proof paper of a character designating densities corresponding respectively to 95 the densities of a supplementary print and thereby producing the camera copy under visual guidance of the tone determiner proof paper and a key plate print thereon substantially as set forth.

In testimony whereof, I have hereunto set my hand at Los Angeles, California, this 24th day of December, 1921.

BENJAMIN FRANKLIN HUTCHISON.
